UNITED STATES PATENT OFFICE

HENRY C. DORRIS AND LINDSAY C. PRITNER, OF JOHNSTOWN, PENNSYLVANIA, ASSIGNORS TO BETHLEHEM STEEL COMPANY, A CORPORATION OF PENNSYLVANIA

CAR BRAKE

Application filed August 21, 1929. Serial No. 387,411.

Our invention relates to new and useful improvements in car brakes and is adapted more particularly for use in connection with mine cars and for similar small cars of this type.

Heretofore when resilient steel brake bands have been used it has been the usual practice to immovably anchor the bands on one side of the wheels to the car body while the bands on the opposite side of the wheels are connected to the brake actuating mechanism for setting or releasing the brakes. When the brake bands are mounted in this manner it has been found that the brake bands and shoes, if they have separate shoes mounted thereon do not contact properly especially after the brake shoes or bands become worn and that they will only engage or contact with the tread of the wheel on that side of the wheels on which the actuating mechanism therefor is attached. Our invention obviates this difficulty.

One of the objects of our invention is to provide a brake having resilient steel brake bands, the ends of which are movably held and manipulated in such a manner as to allow the band when forced downward when the brakes are set to frictionally engage the tread of the wheels, to automatically adjust itself and equalize the pressure of the shoes of the brake bands on the wheels.

Another object of our invention relates to forming the sliding or floating connections between the car body and the brake bands in such a manner as to allow the brake bands when the brakes are set to engage the entire frictional face of the brake shoes or bands, or when the brakes are released allowing the brake bands to float and to be raised out of frictional engagement with the tread of wheels.

Another object of our invention relates to the manner of mounting the brake bands so that when the brake bands are set in applying the brakes the pressure will be equally distributed between the brake bands on the wheels and may be applied either on one pair of wheels on one side of the car or on both sides of the car as illustrated.

A further object of our invention is to

simplify and reduce the cost of constructing the same by making substantially all of the parts of the braking mechanism of stock material at the same time producing an effective brake structure.

Having thus given a general description of our invention, we will now, in order to make the matter more clear, refer to the accompanying three sheets of drawings which form part of this specification and in which like characters refer to like parts:

Fig. 1 is a top plan view of a mine car embodying our invention;

Fig. 2 is a side elevation of the car shown in Fig. 1;

Fig. 3 is an end elevation of the car;

Fig. 4 is an enlarged detail in side elevation illustrating more clearly one of the brake bands applied to the tread of a wheel and the connections for the ends of the brake bands between the car body and the brake bar;

Fig. 5 is a detail top plan view of one of the brake bands, illustrating the end connections;

Fig. 6 is a side elevation of a portion of a car showing a modification; and

Fig. 7 is a vertical transverse section taken on the line 7—7 of Fig. 6.

Referring now to the characters of reference on the drawings: The numeral 1 indicates the car body having wheel hood sheets 2 which extend upwardly from the floor of the car and are open to the side of the car to give access to wheels 3, and braking mechanism as shown in Figs. 1, 2, 6 and 7. Resilient steel brake bands 4, each having a lining or shoe 5 of soft steel or other frictional material are adapted to be applied frictionally against the upper side of the tread surface of the wheels, one end of each brake band 4 is bent angularly and formed into an elongated eye 6 and attached to the car body by means of angle brackets 7 and bolt 8 which pass through the brackets 7 and elongated eye 6. The opposite end of each brake band extends tangentially to the body of the band as at 9, the end 10 of which is folded over and riveted thereto in such a manner as to form an eye 11. This end of

the brake band is also bifurcated as at 12 for receiving the end of the brake-bar 13 which is attached to the end 10 of the brake band by means of a bolt 14 to form a hinge joint. A clevis 15 has its lower end attached to the brake-bar 13 by means of a bolt 16, while the upper end of said clevis 15 is pivoted as at 17 to the inner crank arm end 18 of the rock-shaft 19. Rock-shaft 19 is mounted on the under side of the car body by means of bearings 20 and 21 and support 22 and is held against longitudinal movement by the collars 23 and 24 formed integral therewith which are adapted to engage the sides of bearing 20 and support 22. The outer end of rock-shaft 19 projects beyond the end of the car and is formed with a crank arm 25 bent at right angles to the body of the rock-shaft and also at an angle of substantially 55° to the crank arm 18. The end of crank arm 25 is flattened and pivoted as at 26 to the end of a short rod connection 27, the opposite end of which is pivoted as at 28 to the lower end of brake lever 29, which is fulcrumed as at 30 on the bracket 31 attached to the car end. Brake lever 29 has a tooth 32 formed integral therewith adapted to engage a toothed rack 33 secured to the car end. Above the fulcrum point 30 at a distance equal therefrom to the pivotal point 28 is pivoted as at 34 a long connecting rod 35 which has its opposite end attached to another crank arm 36 of the rock-shaft 37 mounted on the opposite side of the car to rock-shaft 19, to which is attached by means of the crank end 38 another brake rigging similar to the one just described and the same reference numerals will apply thereto. Although we have illustrated a car equipped with a brake rigging on each side thereof, which are duplicates, it will be readily understood that we may in some cases only use a brake rigging on one side of the car or on one of the wheels on each side of the car if desired.

Referring now to the modification shown in Figs. 6 and 7, in order to assist the release of the brake bands or shoes from engagement with the tread of the wheel a helical spring 39 is attached to the tangential end of each of the brake bands by means of a clip 40 while the opposite end is secured by means of a bracket 41 to the car body and in order to adjust the tension of the spring a number of holes 42 are formed in the downwardly extending leg of the bracket 41 in which the hooked end of the spring 39 is secured to give greater or less tension to the spring. Otherwise the construction is the same as described for Figs. 1 to 5.

The operation of the braking mechanism is as follows: Assuming that the parts are in the position shown in the drawings which is the position they will assume when the brakes are set or in frictional engagement

with the upper side of the wheel treads, the operator grasps the handle of the brake lever 29 and releases the tooth 32 from the rack 33 and then swings the brake lever 29 from right to left a sufficient distance to release the brake bands and then allows it to be locked by the tooth 32 reengaging the rack 33 thereby rotating the rock-shafts 19 and 37 through the connecting rods 27 and 35 which is connected to the crank arms 25 and 36. Both of the crank arms 25 and 36 will be rotated oppositely towards the outside of the car as it will be noted that both of the rock-shafts 19 and 37 are of similar construction but are made right and left. As the rock-shafts 19 and 37 are rotated, crank arms 18 and 38 which when the brakes are set are substantially horizontal will both rotate upwardly and outwardly thereby releasing the brake bands and shoes from the wheels, at the same time the opposite ends of the brake bands each having the elongated eye formed therein allows the brake bands to slide or float and release themselves from the entire tread engaging surface of the wheels. When it is desired to reset the brakes the lever 29 is swung from left to right and the operation is reversed.

Although we have described and illustrated our invention in considerable detail, we do not wish to be limited to the exact and specific details thereof, as shown and described, but may use such modifications in, substitutions for, or equivalents thereof, as are embraced within the scope of our invention or as pointed out in the claims.

Having thus described our invention what we claim as new and desire to secure by Letters Patent is:

1. The combination with a car body and a wheel at one side of the car, a rock-shaft arranged parallel to and supported on the car body, a resilient brake band having one end slidably connected to the car body adapted to slide longitudinally when the brakes are set or released, a flexible connection between the rock-shaft and the opposite end of the brake band, means for turning the rock-shaft, and means when the rock-shaft is turned to force the brake band into or out of frictional engagement with the wheel.

2. The combination with a car body and a pair of wheels at one side of the car, a rock-shaft arranged parallel to and supported on the car body, a resilient brake band for each wheel having one end slidably connected to the car body adapted to slide longitudinally when the brakes are set or released, a brake bar pivotally connecting the opposite ends of a pair of the brake bands together, a flexible connection between the rock-shaft and the brake band, a brake lever connected to the rock-shaft for turning said rock-shaft, and means when the

rock-shaft is turned to force the brake bands into or out of frictional engagement with the wheels.

3. The combination with a car body and a pair of wheels at one side of the car, a rock-shaft arranged parallel to and supported on the car body, a crank arm formed on the inner and outer ends of the rock-shaft, a resilient brake band for each wheel, a vertically movable pivotal connection for connecting together the inner ends of each brake band, means for sliding the outer ends of the brake bands, a brake bar for connecting the opposite ends of the brake bands together, a swivel connection between the inner crank arm of the rock-shaft and the brake bar, a manually movable brake lever pivoted to the car, a rod connection between the brake lever and the crank arm on the outer end of the rock-shaft adapted for turning said rock-shaft, and means when the rock-shaft is turned to force the brake bands into or out of frictional engagement with the wheels.

4. The combination with a car body and a pair of wheels at one side of the car, a rock-shaft arranged parallel to and supported on the car body, a crank arm formed on the inner and outer ends of the rock-shaft, means for holding the rock-shaft against longitudinal movement, a resilient brake band for each wheel, an elongated eye formed in one end of each brake band, brackets mounted on the car body, a bolt extending through the elongated eye and brackets adapted to form a slidable connection for the end of the brake band, a vertically movable brake bar for pivotally connecting the two opposite ends of the brake bands together for each pair of wheels at one side of the car, a swivel connection between the inner crank arm of the rock-shaft and the brake bar, a brake lever connected to the crank arm on the outer end of the rock-shaft adapted for turning said rock-shaft, and means when the rock-shaft is turned to force the brake bands into or out of frictional engagement with the wheels.

5. The combination with a car body and a wheel at one side of the car, a resilient brake band mounted above the wheel tread and having one end longitudinally slidably connected to the car body, and vertically movable pivotal means attached to the opposite end of the brake band to force the brake bands into or out of frictional engagement with the wheel.

6. The combination with a car body and a pair of wheels at one side of the car, a rock-shaft arranged parallel to and supported on the car bottom, a crank arm formed on the inner and outer ends of the rock-shaft, collars on the rock-shaft for holding said shafts against longitudinal movement, a resilient brake band for each wheel each having a lining secured thereto, means for slidably mounting one end of each

brake band on the car body, a brake bar for connecting the opposite ends of the two brake bands together to form a hinge joint, a swivel connection between the inner crank arm of the rock-shaft and the brake bar, a manually movable brake lever pivoted to the car, a rod connection between the brake lever and the crank arm on the outer end of the rock-shaft adapted for turning said rock-shaft, and means when the rock-shaft is turned to force the brake bands into or out of frictional engagement with the wheels.

7. The combination with a car body and a pair of wheels at one side of the car, a resilient brake band for engaging the top tread surface of each wheel, means for slidably connecting the outer end of each brake band to the car body and horizontally movable thereto when the brakes are set or released, a vertically movable brake bar for connecting the two inner ends of the brake bands together, and means connected to the brake bar adapted to force the brake bands into or out of frictional engagement with the wheels.

8. The combination with a car body and a pair of wheels at one side of the car, a resilient brake band for engaging the top tread surface of each wheel, a slidable connection for the outer end of each brake band on the car body, a vertically movable brake bar for connecting the two inner ends of the brake bands together between the wheels, a rock-shaft arranged parallel to and supported on the car bottom, a crank arm formed on the inner and outer ends of the rock-shaft, a swivel connection between the inner crank arm of the rock-shaft and the brake bar, a brake lever connected to the crank arm on the outer end of the rock-shaft adapted for turning said rock-shaft, and means when the rock-shaft is turned to move the brake bands into or out of frictional engagement with the wheels.

9. The combination with a car body and a pair of wheels at each side of the car, a resilient brake band for engaging the top tread surface of each wheel, a slidable connection for the outer end of each brake band on the car body, a brake bar for pivotally connecting the two inner ends of each pair of the brake bands together between each pair of wheels on each side of the car, a rock-shaft for each pair of brake bands arranged parallel to and supported on the car bottom, a swivel connection between each brake bar and the rock-shaft on each side of the car, and means adapted to simultaneously rotate each rock-shaft to move the brake bands into or out of frictional engagement with the wheels.

10. The combination with a car body and a pair of wheels at each side of the car, a brake band for engaging the top tread surface of each wheel arranged in pairs on each

side of the car, a slidable connection for the outer end of each brake band on the car body, a brake bar for pivotally connecting the two inner ends of each pair of brake bands together between each pair of wheels, a rock-shaft for each pair of brake bands arranged parallel to and supported on the car bottom near each side thereof, a crank arm formed on the inner and outer ends of each of the rock-shafts, a swivel connection between each of the inner crank arms of the rock-shafts and the brake bar, a brake lever connected to the crank arm on the outer end of each rock-shaft adapted to simultaneously rotate each rock-shaft to move the brake bands into or out of frictional engagement with the wheels.

11. The combination with a car body and a wheel at one side of the car, a resilient brake band mounted above the wheel tread and having one end slidably connected to the car body adapted for horizontal movement in relation thereto, pivotal means attached to the opposite end of the brake band to move the end of the brake band vertically into or out of frictional engagement with the wheel, and a resilient connection between the car body and the brake band adapted to assist in moving the brake band out of frictional engagement with the tread of the wheel.

12. The combination with a car body and a pair of wheels at one side of the car, a resilient brake band mounted above each wheel tread having their outer ends slidably connected to the car body, a brake bar for pivotally connecting the opposite inner ends of the two brake bands together, a rock-shaft arranged parallel to and supported on the car bottom, a crank arm formed on the inner and outer ends of the rock-shaft, a swivel connection between the crank arm on the inner end of the rock-shaft and the brake bar, a brake lever attached to the crank arm on the outer end of the rock-shaft adapted to rotate the rock-shaft, spring connections between the car body and the brake bands adapted to assist in moving the brake bands out of frictional engagement with the tread of the wheels, and means for adjusting the tension of the springs.

13. The combination with a car body and a pair of wheels at each side of the car, a brake band mounted above each wheel adapted for engaging the top tread surface of each wheel and arranged in pairs on each side of the car, a slidable connection for the outer end of each brake band on the car body, a brake bar for pivotally connecting the two inner ends of each pair of brake bands together between each pair of wheels on each side of the car, a rock-shaft arranged parallel to and supported on the car bottom near each side thereof, a crank arm formed on the inner end of each rock-shaft,

a crank arm formed on the outer end of each rock-shaft extending at an angle to the crank arm formed on the inner end of said shaft, a swivel connection between each of the inner crank arms of the rock-shafts and the brake bar, a brake lever pivotally mounted on the car end, a connecting rod between the brake lever and each of the crank arms on the outer ends of the rock-shafts, a tooth on the brake lever, a rack secured to the car end having notches thereon adapted to be engaged by the tooth of the brake lever to hold the brakes in their set positions, and means by the operation of the brake lever adapted to simultaneously rotate each rock-shaft to move the brake bands into or out of frictional engagement with the wheels.

14. The combination with a car body and a pair of wheels at each side of the car, a brake band mounted above each wheel adapted for engaging the top tread surface of each wheel arranged in pairs on each side of the car, a slidable connection for the outer end of each brake band on the car body, a brake bar for pivotally connecting the two inner ends of each pair of brake bands together to form a hinged joint between each pair of wheels on each side of the car, a rock-shaft arranged parallel to and supported in bearings on the car bottom near each side thereof, means for holding the rock-shafts against longitudinal movement, a crank arm formed on the inner end of each rock-shaft, a crank arm formed on the outer end of each rock-shaft, a swivel connection between each of the inner crank arms of the rock-shafts and the central portion of the brake bars, a brake lever pivotally mounted on the car end for operating the brake rigging, a connecting rod between the brake lever and each of the crank arms on the outer ends of the rock-shafts, means for holding the brake lever in their set positions, means when the brake lever is operated to simultaneously rotate each rock-shaft, and means by the action of the rock-shaft when the brakes are set for distributing an equal pressure between the brake bands on the wheels.

In testimony whereof we hereunto affix our signatures.

HENRY C. DORRIS.
LINDSAY C. PRITNER.
